UNITED STATES PATENT OFFICE.

E. S. SCRIPTURE, OF NEW HAVEN, CONNECTICUT.

WINDOW-FASTENER.

Specification of Letters Patent No. 19,588, dated March 9, 1858.

To all whom it may concern:

Be it known that I, ELIPHALET S. SCRIP-
TURE, of New Haven, in the county of New
Haven and State of Connecticut, have in-
5 ventioned a new and useful Improvement in
Window Fasteners or Locks; and I do hereby
declare that the following is a full, clear,
and exact description of the same, reference
being had to the annexed drawings, making
10 a part of this specification, in which—

Figure 1 is a side sectional view of my
improvement. Figs. 2, 3 and 4 are perspectives
of the same. Fig. 5, is a perspective
sketch of the model.

15 Therefore, I proceed to fully describe
my invention.

A represents the under half of a divided
tube, or cylinder, provided with half circle
20 heads *a*, *a*, at, or near each end, provided
each with a central semicircle aperture.

B represents a small metallic piece having
upon it a small projection or nipple, rising
up from near its center as at *b*, which I
25 denominate a vibrating tracer, the same
being fitted for, and placed in, or near, the
center and bottom of said lower half tube
A in a recess provided for it.

C represents a piece of india rubber which
I call a pillow block, and is placed between
30 the forward head *a*, and the tracer block B.

D represents a piece of wood placed be-
tween the back head *a*, and the tracer block
B, and is called the regulating block.

E represents a shaft, or bolt, the back
35 end, (as at little C,) representing a square,
to receive a key, or crank, the opposite, or
forward end is provided with a flange, re-
presented at *d*, and is larger in its diameter
40 than the bolt E, said flange representing
about a quarter circle, and formed into an
abrupt incline plane, or wedge; about a
half inch back of this flange *d*, commences
45 a spiral groove, shown at *e*, commencing
very abrupt, and as it recedes back, and
around the bolt E it terminates at about
two thirds of its circumference in a dead
plane, or rather returning again toward
50 the forward end, this bolt E, is placed in
the half circles *a* *a*, at the same time resting
upon and over the pillow block C, the regu-
lating block D, and tracer B, receiving in
55 the groove *e*, the tracer nipple *b*.

F represents the upper half of the tube
A which is provided with three half heads
55 or partitions *a* *a* *a*, having in them corre-

sponding semicircles to fit over bolt E, so
that when placed over, and secured to the
lower half tube A, it serves to confine all
parts snugly together *f* *f* *f* *f* representing
wings, with guide pin and hole *g* *g*, which 60
serve to secure the half tubes together, and
keep all from turning when in use.

G represents what I term a catch stud,
which is to be properly, and firmly at-
tached to the outer sash XI, said catch be-
ing provided with a hole through it, the
upper part presenting a downward pro-
jecting flange *h*, which is in form of a
wedge, or abrupt plane, which corresponds
with the quarter circle flange *d*, upon bolt 70
E; when all being thus arranged, with the
tube attached to, or inserted in the inner
sash X as is shown in Fig. 1 by then ap-
plying the key, or crank upon the square
75 *c*, of bolt E, and turning to the right, the
bolt E advances rapidly forward, until its
quarter circle flange *d*, takes firmly behind
the flange *h*, upon stud G, when the termi-
nating incline plane in the bolt groove *e*, 80
commences to drive the tracer B *b*, for-
ward against the rubber pillow block C,
and hauling back upon the catch stud and
flange G *h*, thereby drawing, and holding
85 together the two sashes under the elastic
pressure of india rubber pillow block C; 85
which also serves, (by its yielding quality)
to compensate for any little imperfection
of work, or variations in space; the regu-
lating block D, serves to hold the tracer
90 B *b*, to its place, as well as to regulate its
position in the recess of tube, by diminish-
ing or adding to its length, providing a
cheap, and ready mode of regulating the
pinch, or draft, upon the incline planes. 95

The advantages claimed for this improve-
ment, are firstly its extreme simplicity, its
small, compact and convenient form, its
small cost, its ready adaptability, and
strong, effective operation and security,
drawing the window, both together, and
100 downward, at the same time when the neck
groove *i*, back of flange *d*, is made eccen-
tric for the purpose. Secondly its being
tubular, allowing it to be inserted within
the sash, renders it much less liable to in-
jury from external causes, and much less
105 in the way in cleaning the windows.
Thirdly its partaking of the character of
a lock, from which the key may be re-
moved, provides far more safety against 110

roguish children, or criminal burglars. Fourthly it is a sovereign remedy for rattling windows.

Having thus fully described the nature 5 of my invention, and set forth its advantages, I will say that I am aware that bolts with spiral grooves formed in them, have been used before, for various purposes, I therefore do not claim such; but,

0 What I do claim as new, and desire to secure by Letters Patent, is—

The vibrating tracer B b, (or in other

words, small section of a screw nut allowed to be vibratory in its operation) in combination with the elastic pillow block C, the 15 regulating block D, the bolt E, and the catch stud G, with their flanges and incline planes, all being secured in a two part tube, and all being arranged substantially in the manner, and for the purposes set forth.

ELIPHALET S. SCRIPTURE.
